UNITED STATES PATENT OFFICE.

AUGUSTUS H. HEISEY, OF IDLEWOOD, PENNSYLVANIA.

DESIGN FOR A GLASS VESSEL.

SPECIFICATION forming part of Design No. 28,181, dated January 18, 1898.

Application filed November 12, 1897. Serial No. 658,346. Term of patent 3½ years.

To all whom it may concern:

Be it known that I, AUGUSTUS H. HEISEY, a resident of Idlewood, in the county of Allegheny and State of Pennsylvania, have invented a new and original Design for Glass Vessels; and I do hereby declare the following to be a full, clear, and exact description thereof.

My invention relates to designs for vessels formed of glass.

In the accompanying drawing I have illustrated by a perspective view a glass vessel embodying my design.

The letter *a* designates the base of a glass vessel, and just above said base is the notched ring *a'*. Above the notched ring *a'* is the bulb-

ous portion *b*, projecting out beyond the base *a*. Above the bulbous portion *b* is the notched ring *c'*. Extending up from the upper end of the bulbous portion *b* is the straight outwardly-flaring portion *c*. On the upper edge of the outwardly-flaring portion *c* is a series of beads *d*, also formed of glass.

What I claim is—

The design for a glass vessel as herein shown and described.

In testimony whereof I, the said AUGUSTUS H. HEISEY, have hereunto set my hand.

AUGUSTUS H. HEISEY.
